No. 36,790.

Patented February 9, 1904.

UNITED STATES PATENT OFFICE.

GABRIEL HOSTACHY, OF PLAINFIELD, NEW JERSEY.

DESIGN FOR A GLOVE.

SPECIFICATION forming part of Design No. 36,790, dated February 9, 1904.

Application filed July 28, 1903. Serial No. 167,359. Term of patent 14 years.

To all whom it may concern:

Be it known that I, GABRIEL HOSTACHY, a citizen of the Republic of France, residing at Plainfield, in the county of Union and State of 5 New Jersey, have invented a new, original, and ornamental Design for Gloves, of which the following is a specification, reference being had to the accompanying drawing, forming part thereof.

10 The figure is a plan of the back of a glove, showing my new design.

What I claim as new, and desire to secure by Letters Patent, is—

The ornamental design for a glove, as herein shown.

G. HOSTACHY.
